FIG. 1

FIG. 2

FIG. 3

FIG. 1 is a top plan view of a diamond or similar article showing my new design;

FIG. 2 is a bottom plan view thereof; and

FIG. 3 is a side elevational view thereof.

The characteristic features of the invention reside in the utilization of a diamond having a circular girdle with the table formed with the upper surface thereof having straight lines forming two overlapping equilateral triangles forming the "Star of David" or six pointed star as shown.

I claim:

The ornamental design for a diamond or similar article, as shown and described.
